UNITED STATES PATENT OFFICE.

JOHN T. GARTRELL, OF NAPAVINE, WASHINGTON.

STUMP BURNER.

1,413,112.

Specification of Letters Patent. Patented Apr. 18, 1922.

Application filed December 21, 1920. Serial No. 432,176.

To all whom it may concern:

Be it known that I, JOHN T. GARTRELL, a citizen of the United States, and resident of the town of Napavine, county of Lewis, 5 State of Washington, have invented certain new and useful Improvements in Stump Burners, of which the following is a specification:

This invention relates to improvements in 10 stump burners; more particularly it relates to devices of that character wherein a plurality of sheet metal sections are assembled to form an enclosure about a stump, whereby, when the stump is fired, the flames will 15 be confined thereto, a better draft will be provided and the stump more quickly and thoroughly destroyed.

The principal object of the present invention is to provide a stump burner of the 20 above character comprising a plurality of similar sections, which may be assembled in any required or desired numbers according to the diameter of the stump which it is desired to enclose for burning, and which may 25 be provided with dampered openings for the admittance of air and the discharge of smoke.

Other objects of the invention reside in the detail construction of the sections used 30 in the construction of the burner, and in the means whereby these sections are joined together and held in assembled relation while the device is in use.

In accomplishing these and other objects 35 of the invention, I have provided the improved details of construction, the preferred forms of which are illustrated in the accompanying drawings, wherein—

Figure 1 is a side elevation of a stump 40 burner constructed and assembled according to the present invention.

Figure 2 is a plan view of the same, shown partly in section for the purpose of better illustration.

Figure 3 is a central vertical section 45 through the burner; the latter being in position for burning about a stump.

Figure 4 is an enlarged, sectional view, 50 showing parts of a lower and a superimposed upper section, and means whereby the upper section may be supported during assembly of the parts.

Figure 5 is a perspective view of one of 55 the locking devices whereby the vertical sections are joined together.

Referring more in detail to the several

views of the drawings wherein like reference numerals designate the same or like parts—

1 designates the stump burner taken as a 60 whole. This in a preferred form, is constructed of a plurality of radially curved sheet metal sections 2, all of the same size and shape and arranged vertically edge to edge to form a circular enclosure about the stump which is to be burned; the sections, 65 when assembled, being joined together and securely held in functional relation by the use of interlocking means, presently described, at their adjacent edges.

Upon the upper edges of these lower sections are supported corresponding upper sections 4, which are of the same width at 70 their bases as the sections whereon they are supported but are tapered toward their upper ends so that, when their tapered edges 75 are brought together the sections will form somewhat a conically shaped cover above the stump. These upper sections are curved radially to fit the curvature of the lower sections and are also curved longitudinally, as 80 shown best in Figure 3, to give the most clearance within the housing.

I will state here that I do not wish to limit the construction to any particular number 85 of sections, since it is apparent that any desirable or required number may be assembled, according to the size of the stump to be burned at any particular time. However, in the manufacture of these burners it is intended to curve the bottom sections on a 90 radius equal to the radius of a housing that would be formed by the assembling of six sections, and to include eighteen upper and lower sections with each complete outfit. This number when assembled will be sufficient to accommodate the largest of stumps 95 and may be assembled to form two, or three housings of sufficient size for burning smaller stumps.

For the purpose of providing an outlet 100 for the escape of smoke from the burner, the upper part of the enclosure is truncated, leaving a central opening 6. This is equipped with a cover or lid 7, which is preferably attached to one of the sections 4 by means of 105 a small chain 8, and which may be adjustably placed over the opening to regulate the size. To provide for a draft, some of the lower sections, as is shown in Figures 1 and 3, are provided with openings 10 in their 110 lower portions for the admittance of air into the burner, and are equipped at opposite

sides of the openings with guide flanges 11 between which doors 12 are slidably mounted for adjustment over the openings as required for the proper admittance of air.

5 The preferred means of joining the lower sections of the housing is shown in Figures 1, 2 and 5, wherein 15 designates eyelets that are fixedly attached to corresponding edges of all the sections 2 near their upper and 10 lower edges, and 16 designates hook like members that are rigidly fixed cooperatively to the opposite edges of all the sections and which have downwardly extending ends 17 adapted to be projected into the eyelets of 15 the adjacent sections in such manner as to hingedly lock the sections together. This construction affords a hinge like connection that permits variation in the size of the 20 burner and affords easy assembling or dis-

25 The upper sections are likewise separably joined together by means of eyelets 20 fixed adjacent to corresponding edges, and hooks 21 that are pivotally fixed to cooperate there- 30 with on the opposite edges of the sections, and at their lower ends, adjacent the oppo- 35 site corners, they are each provided with depending hooks 25 adapted to hook into eyelets 26 fixed to the upper edges of the lower sections to retain them in position, and against outward movement, but which permits a certain desired flexibility. Each 40 of the lower sections is provided on its inner face adjacent its upper end with an in- 45 wardly curved, flanged plate 28 which serves as an abutment for retaining the section supported thereon from inward movement.

To facilitate the erection of the upper part of the housing, each section 4 has 45 pivotally fixed thereto, centrally at its lower end, a vertically swinging bar 30 pro- 50 vided along its lower end with ratchet teeth 31 adapted to lock within a flange plate 32 secured to the lower section. These bars are 55 intended to hold their respective sections at a definite incline while they are being as- 60 sembled and until they can be locked to- 65 gether by the hooks 21.

Assuming that the sections are so con- 70 structed, it is apparent that they may be as- 75 sembled in required numbers to suit stumps of different sizes, the larger the stump the more sections being required.

It is also seen that the hooks provided 80 afford easy and quick assembling or dis- 85 sembling of the parts.

Such devices can be made of various sizes, and comprising varying numbers of sec- 90 tions, some of which should be dampered

for the admittance of air to afford sufficient 60 draft for easy burning, and by their use stumps can be quickly, safely and thoroughly 65 burned, as the flames and heat is confined and directed against the stump enclosed.

Having thus described my invention, what 65 I claim as new therein and desire to secure by Letters-Patent, is:

1. A stump burner comprising a plurality 70 of cylindrically curved, lower plate sections of like size and shape, arranged edge to edge to form a circular enclosure about a stump, inwardly curved upper plate sections disposed upon the lower sections and tapered 75 toward their upper ends, each of said upper and lower plate sections being provided, ad- 80 jacent their edges, with interlocking devices whereby the sections may be separably joined together, and means whereby said upper sections may be supported at adjusted positions to regulate the inclination thereof and the 85 amount of open space above the stump.

2. A stump burner of the class described comprising in combination a plurality of cylindrically curved, rectangular plates ar- 85 ranged edge to edge to form a circular en- 90 closure, said plates having interlocking mem- 95 bers at their vertical edges whereby they are separably joined together, and having hook receiving devices at their upper edges, a 100 plurality of tapered sections superimposed upon said lower sections forming a dome shaped cover over said enclosure, and having hooks fixed thereto at their lower edges en- 105 gaging said hook receiving devices on the lower sections to hingedly attach the upper sections, ratchet bars fixed pivotally to the upper sections to depend along the lower sections and anchor plates fixed to said lower sections engageable by said bars to re- 110 tain the upper sections at adjusted, inwardly inclined positions while the parts are being assembled.

3. A stump burner comprising a plurality 105 of lower plate sections, arranged edge to edge to form a circular enclosure, flanged plates secured to said lower sections adj- 110 acent their upper edges, inwardly curved upper plate sections disposed upon the lower sections and prevented from inward move- 115 ment by said flanged plates, means secured to the adjacent edges of said upper and lower sections whereby the upper sections may be adjusted to and held at different inclined positions.

Signed at Seattle, Washington, this 16th 115 day of December, 1920.

JOHN T. GARTRELL.
